AUTODYNE CIRCUIT

Walter van B. Roberts, Princeton, N. J., assignor
to Radio Corporation of America, a corpora-
tion of Delaware

Application January 31, 1930, Serial No. 424,792

14 Claims. (Cl. 250—20)

My present invention relates to heterodyne systems, and more particularly to a superheterodyne receiver employing an autodyne circuit.

It has been suggested in the past that superheterodyne receiving circuits be constructed so as to utilize a first autodyne tube circuit. That is to say, the antenna was to be coupled to a tube having two independent tuned oscillation circuits in its input; one of these circuits was to be tuned 10 to the signal to be received, while the other was to be tuned to the frequency of the heterodyne oscillations to be employed for producing the intermediate frequency. Furthermore, the two circuits were to be arranged so that they did not affect each other during tuning, and oscillations in the heterodyne circuit were not to set up oscillations in the signal circuit with consequent radiation from the antenna.

However, trouble is encountered when it is attempted to mount the rotors of the signal and local oscillation condensers, on a common shaft for uni-control tuning, in a gang of condensers, shielded by a so-called "bath-tub" metallic housing. One of the chief difficulties encountered is that in the bridge arrangements heretofore used, such as Fig. 1 herein, no two sets of condenser plates are at the same potential, consequently a gang condenser with rotors at a common potential cannot be used.

Accordingly, I have invented a method of, and devised means for, employing an autodyne circuit in a superheterodyne receiver wherein no local energy is radiated from the antenna, and wherein the rotors of the signal and local circuits 35 may be mounted on the common shaft of a bathtub housing without having the condenser rotors at different potentials.

Another important object of the invention is to provide a heterodyne circuit employing the autodyne principle, and means for preventing 40 radiation from the antenna by the tuned local oscillation circuit, the means including a tuned signal circuit coupled to an inductance, the latter being connected at one end thereof to the tuned local oscillation circuit so that signal current does not produce current in the local oscillation circuit.

Another object of the invention is to provide a frequency changing circuit in which the grid bias of the electron discharge tube is secured by self-biasing means, rather than by positive biasing means, and the signal and local circuits so arranged in the tube input that no local energy is fed into the signal circuit.

Still other objects of the invention are to improve generally the simplicity and efficiency of

frequency changing circuits of the autodyne type, as employed particularly in superheterodyne receivers, and to provide a frequency changing circuit which is not only durable and reliable in operation, but is readily adapted to economical manufacture for use in superheterodyne receivers.

The novel features which I believe to be characteristic of my invention are set forth in particularity in the appended claims, the invention itself, however, as to both its organization and method of operation will best be understood by reference to the following description taken in connection with the drawing in which I have indicated diagrammatically one circuit organization whereby my invention may be carried into effect.

In the drawing,

Fig. 1 shows diagrammatically a frequency changing circuit of the autodyne type.

Fig. 2 shows a similar circuit embodying my invention.

Referring now to the accompanying drawing in which like characters of reference indicate the same parts in the different figures, I have shown in Fig. 1 a frequency changing circuit employed in connection with the first electron discharge device 25 of a superheterodyne receiver, and which circuit is known as the Pressley circuit.

This latter circuit is briefly described herein to bring out more clearly the advantages secured 30 by the present invention, and consists of the usual grounded antenna A coupled by a transformer as at M, to a signal circuit S, tuned by a condenser 1'. Between the control electrode and cathode of the tube 1 is connected a local oscillation circuit 35 O, which includes an inductance 2 and a variable condenser 3 shunted across the inductance, there being a fixed capacity K in series between the cathode and the inductance 2.

The secondary 4, which functions as the inductance of the signal circuit S, has one of its terminals connected to an intermediate point 5 of the oscillation inductance 2, while a source C is connected between the cathode and the inductance 4 of the signal circuit for biasing the 45 grid of the tube. The anode of the tube is energized from a source B through the primary 6 of a transformer M', there being a feed back, or tickler, coil 7 in the anode circuit in series with the source B. A by-pass condenser 8 is shunted 50 across the primary 6.

The output of the frequency changing tube 1 is impressed upon the secondary 9 of the transformer M', it being understood that the secondary 9 is connected in the input of the first stage of 55

the intermediate frequency amplifier in a manner well known to those skilled in the art. The intermediate frequency amplifier may be followed by any other type of circuit and utilizing means well known to those desiring to vary the possibilities thereof, when the present invention is employed in superheterodyne practice, such additional circuits not being shown for the sake of simplicity.

10 The circuit shown in Fig. 1 is operated by tuning the signal circuit S to the desired signal frequency, and tuning the local oscillation circuit O to a frequency which will heterodyne with the signal frequency to produce a difference frequency equal to the frequency to which the intermediate frequency amplifier is tuned. Of course, it simplifies the operation of the superheterodyne receiver when the variable condensers 1 and 3 can be arranged in gang construction in a bath-tub housing for shielding purposes, and the rotors of the two condensers mounted on a common actuating shaft for uni-control.

For example, one of the advantages to be secured by such construction is not only the simultaneous tuning of the two circuits, but the fact that the rotors of each of the condensers may be so relatively shaped that a constant frequency difference may be maintained between the two circuits which is equal to the intermediate frequency being employed. However, actual experience has shown that the circuit in Fig. 1 does not lend itself to such construction. That is to say, the condenser rotors, in the circuit of Fig. 1, cannot all be connected together on a common shaft in a bath-tub shielding housing.

By designing and arranging the circuit as shown in Fig. 2, this disadvantage may be effectively eliminated. Thus, in Fig. 2 there is shown an antenna circuit A including a capacity 1' therein, and an anti-resonant signal circuit S in series with the antenna condenser 1'. The signal circuit includes the variable condenser 10 and a coil L connected across the variable condenser 10. Condenser K, shunted by a high resistance R, is connected in series with condenser, or tube input capacity C', the latter being shunted by the tube input resistance. A blocking condenser B, and the grid leak R, are employed in the grid circuit to maintain the bias on the grid of the tube 1, rather than employing the source which might equally well have been employed, for example in place of condenser B.

The local oscillation circuit O which includes the inductance 2 and the variable condenser 3, is connected in series with a coil N, the latter being coupled at M to the coil L. The biasing condenser B is connected in series between the control electrode of tube 1 and the coil N. The anode of the tube is energized from source B through the primary 6 of the transformer M' the primary being shunted by the condenser 8, the tickler, or feed back, coil 7 being connected in series with the primary 6 and the source B, and being further coupled to the inductance 2 of the local oscillation circuit. As in the case of Fig. 1, the difference frequency of the combined signal and local frequencies is impressed upon the secondary 9 of the transformer M', and then amplified by the intermediate frequency amplifier, and the aforescribed subsequent utilization circuits and means.

The operation and advantages of the invention will now be described. If coil N were open circuited, the grid of tube 1 would assume a potential

difference across coil L. Now, assume that coil N is connected in circuit, and coupled to coil L sufficiently so that coil N has a potential difference generated between its terminals due to current in coil L, which potential difference is exactly equal to the aforementioned grid potential. It follows that the potential at the bottom of coil N is zero as a result of current in coil L; hence, current in coil L does not produce any current in the oscillation circuit O.

And, therefore, from well known reciprocity theorems it follows that oscillations in oscillation circuit O will not produce potential difference between antenna and ground, and hence will not cause radiation. In practice, it has been found that while a resistance in parallel with condenser K is theoretically required to balance the effect of the tube input resistance, it is not critical, and, that at ordinary intermediate frequencies, can be dispensed with entirely if it is preferred to bias the grid by other means.

While I have indicated and described one arrangement for carrying my invention into effect, it will be apparent to one skilled in the art that my invention is by no means limited to the particular organization shown and described, but that many modifications may be employed without departing from the scope of my invention as set forth in the appended claims. For example, oscillations generated by separate means may be impressed upon the circuit O rather than be generated by circuit O itself in cooperation with tickler coil 7.

What I claim is:

1. In a receiver of the superheterodyne type 35 wherein transmitted signal modulated carrier frequency energy is intercepted and combined with locally generated oscillations to produce an intermediate frequency, an electron discharge device having an output circuit and an input circuit said input circuit being electrically connected to an antenna system, an oscillation circuit connected in said input circuit adapted to be tuned to the frequency of the desired incoming carrier energy, a second oscillation circuit, means 40 for connecting said circuit in said input circuit, means for coupling the output circuit of said space discharge device to said second named oscillation circuit to facilitate the transfer of energy from said output circuit to said input circuit for producing oscillations, said second named oscillation circuit having means for controlling the frequency of the locally generated oscillations, said connecting means for the second oscillation circuit comprising a link circuit coupled 45 to the first named oscillation circuit, said coupling being arranged so as to provide a voltage at one terminal of the second named tuned circuit to maintain the terminals of said second named tuned circuit as respects its connection in 50 the input circuit of said space discharge device at zero potential with respect to each other and one terminal of the first named tuned circuit.

2. In combination an electron discharge device having an input circuit and an output circuit, 65 said input circuit thereof being linked with said output circuit to facilitate the transfer of energy from said output circuit to said input circuit thereof for producing oscillations, a tuned circuit for controlling the frequency of said oscillations connected in said input circuit, a second 70 tuned circuit tuned to a different frequency than said first named tuned circuit also connected in said input circuit and means for eliminating coupling between said two oscillating circuits through 75

the inherent capacity of the space discharge device comprising a link circuit coupled to the second named tuned circuit and connected in series with the first named tuned circuit across the input of the space discharge device for opposing energy fed from one of the tuned circuits to the other through the said inherent capacity of the space discharge device whereby said two tuned circuits may be operated at very nearly the same frequency without the transference of the energy from one to the other:

3. In an autodyne type circuit adapted for use as a source of locally generated oscillations and as a frequency changer in superheterodyne type circuits, an electron discharge device having an input circuit and an output circuit, said input circuit thereof being linked with said output circuit to facilitate the transfer of energy from said output circuit to said input circuit thereof for producing oscillations, a tuned circuit in said input circuit for controlling the frequency of said oscillations, a second tuned circuit tuned to a different frequency from said first named circuit also connected to said input circuit, capacity between said two tuned circuits including the natural capacity inherent between the various elements of the space discharge device, said circuits being traversed by currents of such high frequency as to make appreciable the coupling between said tuned circuits due to the said capacity and through which coupling high frequency energy may be transferred from one of said tuned circuits to the other and means comprising a linked circuit adapted to have energy transferred thereto from said second named tuned circuit connected in said input circuit for opposing energy transferred from said second named circuit through the space discharge device capacities to said first named tuned circuit whereby said two tuned circuits may be operated at very nearly the same frequency without the transference of energy from one to the other.

4. In a receiver of the superheterodyne type wherein transmitted signal modulated carrier frequency energy is intercepted at the receiver and combined with locally generated oscillations to produce an intermediate frequency and wherein it is desirable to have the frequency of the locally generated oscillations closely approximate the frequency of the carrier energy, an electron discharge device having an input circuit adapted to be electrically connected to an antenna system, an output circuit, said input circuit being linked with said output circuit to facilitate the transfer of energy from said output circuit to said input circuit for producing oscillations, a tuned circuit in said input circuit for controlling the frequency of said last-named oscillations, a second tuned circuit in said input circuit tuned to the frequency of the carrier energy, electrical coupling between said two tuned circuits including the natural capacity inherent between various elements of the space discharge device and through which coupling energy may be transferred from said first named tuned circuit to said antenna system and means comprising a linked circuit adapted to have energy transferred thereto from said second named tuned circuit for opposing energy transferred from said first named tuned circuit through said electrical coupling to said antenna system whereby the locally generated oscillations are substantially prevented from being communicated to the said antenna system.

5. In a receiver of the superheterodyne type

wherein transmitted signal modulated carrier frequency energy is intercepted and combined with locally generated oscillations to produce an intermediate frequency, an electron discharge device having an output circuit and an input circuit said input circuit being coupled to an antenna system, an oscillation circuit including a variable condenser having a stator and a rotor connected in said input circuit adapted to be tuned to the frequency of the desired incoming carrier energy, a second oscillation circuit including a condenser having a rotor and a stator, means for connecting said circuit in said input circuit, means for coupling the output circuit of said space discharge device to the input circuit thereof to facilitate the transfer of energy from said output circuit to said input circuit for producing oscillations, said condenser in said second named oscillation circuit comprising means for controlling the frequency of the locally generated oscillations, said connecting means for the second oscillation circuit comprising a link circuit coupled to the first named oscillation circuit and arranged so as to transfer electrical energy from the first named oscillation circuit to the second so as to maintain the terminals of said second named tuned circuit as respects its connection in the input circuit of said space discharge device at the same potential as one terminal of the first named tuned circuit whereby the rotors of said two condensers are maintained at the same potential and a uni-control means for varying said two condensers simultaneously.

6. In a signalling system, an electronic tube, input and output circuits therefor, a pair of differently tuned oscillation circuits in said input circuit both thereof being adapted to impress voltage developed therein upon the input elements of the tube, means for connecting a terminal of each of said oscillation circuits to a point of fixed potential, coupling between said circuits including the natural capacity inherent between different portions of said system, said circuits being traversed by currents of such high frequency as to make appreciable the inherent coupling between them and through which coupling energy from one of said oscillation circuits may be transferred to the other thereof, a link circuit connecting the other terminals of said oscillation circuits, said link circuit including means for impressing energy from one oscillation circuit to the other of phase and amplitude to oppose the energy transferred through said inherent coupling.

7. In a signaling system, an electric tube, input and output circuits therefor, a pair of differently tuned oscillation circuits in said input circuit both thereof being adapted to impress voltages developed therein upon the input elements of the tube, tuning means for said oscillation circuits comprising fixed and movable elements, means for connecting a terminal of each of said oscillation circuits to a point of fixed potential whereby the movable elements of said tuning means may be connected together by a common operating means, coupling between said circuits including the natural capacity inherent between different portions of said system, said circuits being traversed by currents of such high frequency as to make appreciable the inherent coupling between them and through which coupling energy from one of said oscillation circuits may be transferred to the other thereof, means for connecting the other terminals of said oscillation circuits, said last named means including a

device for impressing energy from one oscillation circuit to the other of phase and amplitude to oppose the energy transferred through said inherent coupling.

- 5 8. In a signalling system, an electronic tube, input and output circuits therefor, a pair of differently tuned oscillation circuits in said input circuit both thereof being adapted to impress voltage developed therein upon the input elements of the tube, tuning condensers for said oscillation circuits each thereof comprising stator and rotor elements, means for connecting the rotor side of each of said oscillation circuits to a point of fixed potential thereby permitting the 10 rotors of said tuning condensers to be electrically connected by a common operating means, coupling between said circuits including the natural capacity inherent between the various elements of said system, said circuits being traversed by 15 currents of such high frequency as to make appreciable the inherent coupling between them and through which coupling energy from one of said oscillation circuits may be transferred to the other thereof, means for connecting the other terminals of said oscillation circuits, said last named means including a device for impressing energy from one oscillation circuit to the other of phase and amplitude to oppose the energy transferred through said inherent coupling.
- 20 9. In a signalling system, an electronic tube, input and output circuits therefor, a pair of differently tuned oscillation circuits in said input circuit, both thereof being adapted to impress voltage components developed therein upon the input elements of the tube, tuning means for each of said oscillation circuits comprising fixed and movable elements, means for linking the output circuit of said tube to one of said oscillation circuits to facilitate the transfer of energy from 25 said output circuit to said oscillation circuit for producing oscillations of a frequency determined by the tuning of said oscillation circuit, means for connecting a terminal of each of said oscillation circuits to a point of fixed potential whereby the movable elements of said tuning means may be connected together by common operating means, coupling between said circuits including the natural capacity inherent between different elements of said system, said circuits being traversed by currents of such high frequency as to make appreciable the inherent coupling between them and through which coupling energy from one of the oscillation circuits may be transferred to the other thereof, means for connecting the other terminals of said oscillation circuits, said last named means including a device for impressing energy from one oscillation circuit to the other of phase and amplitude to oppose the energy transferred through said inherent coupling.
- 30 10. In a signalling system an electronic tube, input and output circuits therefor, a pair of differently tuned oscillation circuits in said input circuit both thereof being adapted to impress voltage components developed therein upon the input elements of the tube, tuning means for each of said oscillation circuits comprising fixed and movable elements, a source of signalling energy, means for connecting one of said oscillation circuits to said source, means for linking the output circuit of said tube to the other of said oscillation circuits to facilitate the transfer of energy from said output circuit to the last named oscillation circuit for producing oscillations of a frequency determined by the tuning 35

- 75

of said oscillation circuit, means for connecting a terminal of each of said oscillation circuits to a point of fixed potential whereby the movable elements of said tuning means may be connected together by common operating means, coupling between said circuits including the natural capacity inherent between different elements of said system, said circuits being traversed by currents of such high frequency as to make appreciable the inherent coupling between them and through which coupling a portion of said produced energy may be transferred back to said source of signalling energy and radiated therefrom, means for connecting the other terminals of said oscillation circuits, said last named means including a device for transferring energy from one oscillation circuit to the other of phase and amplitude to oppose the energy transferred through said inherent coupling.

11. In a signalling system an electronic tube, input and output circuits therefor, a pair of differently tuned oscillation circuits in said input circuit, both thereof being adapted to impress voltage components developed therein upon the input elements of the tube, tuning condensers for said oscillation circuits each thereof comprising stator and rotor elements, means for connecting the rotor side terminals of each of said oscillation circuits to a point of fixed potential thereby permitting the rotors of said tuning condensers to be electrically connected by a common operating means, coupling between said circuits including the natural capacity inherent between the various elements of said system, said circuits being traversed by currents of such high frequency as to make appreciable the inherent coupling between them and through which coupling energy from one of said oscillation circuits may be transferred to the other thereof, means for linking the output circuit of said tube to one of said oscillation circuits to facilitate the transfer of energy from said output circuit to said oscillation circuit for producing oscillations of a frequency determined by the tuning of said oscillation circuit, a source of incoming signalling energy, means for coupling the other of said oscillation circuits to said source, means for connecting the other terminals of said oscillation circuits, said last named means including a device for transferring energy from one oscillation circuit to the other of phase and amplitude to oppose the energy transferred through said inherent coupling and an intermediate frequency circuit associated with said output circuit.

12. A heterodyne receiver comprising an antenna, a frequency changing tube, a resonant signal circuit between the antenna and tube input including a variable condenser, a local oscillation resonant circuit coupled to the tube and including a variable condenser, said two resonant circuits having inherent coupling between them through which inherent coupling, energy in one circuit is transferred to the other circuit, energy transfer means including a coupling coil between the local and signal circuits for transferring energy from one circuit to the other in a sense to oppose the effect of the energy transferred through the inherent coupling between the two resonant circuits whereby said two circuits may be made resonant to frequencies differing from each other only by small amounts, and means for maintaining one terminal of one of said condensers at the same fixed potential as a terminal of the other condenser.

13. In a heterodyne receiver a frequency chang-

ing tube having input and output circuits, said input circuit including a resonant signal circuit having a variable tuning means adapted to tune said resonant circuit to any one of a plurality of signal frequencies within a predetermined band, a local oscillation resonant circuit coupled to the tube and including a variable tuning means for tuning said local oscillation circuit to any frequency within a predetermined band, a single means for operating both of said variable tuning devices simultaneously, said two resonant circuits having inherent coupling between them through which energy in one circuit is transferred to the other circuit, energy transfer means including a coupling device between the local and signal circuits for transferring energy from one of said circuits to the other thereof in a sense to oppose the effect of energy transfer through the inherent coupling between the two circuits whereby said two circuits may be made resonant to frequencies differing from each other only by very small amounts and means for maintaining one terminal of one of said condensers at the same fixed potential as a terminal of the other condenser.

14. In a receiver of the superheterodyne type, a frequency changer circuit including an electronic tube provided with input and output circuits, a resonant signal circuit in said input circuit said resonant signal circuit including a variable condenser, a second resonant circuit in the input circuit of said tube said second circuit including a variable condenser for tuning the circuit to the heterodyning frequency, said two resonant circuits having inherent coupling between them through which coupling energy in one circuit is transferred to the other circuit, coupling means between said two resonant circuits for transferring energy from one circuit to the other in a sense to oppose the effect of the energy transferred through said inherent coupling to thereby permit said two resonant circuits to be made resonant to frequencies differing from each other only by small amounts said condensers being arranged so that one terminal of one and one terminal of the other are at the same fixed potential to thereby permit uni-control of the condensers.
